Primary Examiner—Ted Shooman*Assistant Examiner*—C. Tuttle*Attorney, Agent, or Firm*—Ernestine C. Bartlett**[57]****CLAIM**

The ornamental design for a click on hair trimmer device for a dry shaver, as shown.

DESCRIPTION

FIG. 1 is a perspective view showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The unshaded region of the bottom surface forms no part of the claimed design.
